Inventor:

William Lane

By his Ally, Edward Lane

UNITED STATES PATENT OFFICE.

WILLIAM LANE, OF SAN FRANCISCO, CALIFORNIA.

PEN OR PENCIL HOLDER.

SPECIFICATION forming part of Letters Patent No. 281,525, dated July 17, 1883.

Application filed September 4, 1882. (No model.)

To all whom it may concern:

Be it known that I, WILLIAM LANE, a citizen of the United States, residing in the city and county of San Francisco, State of California, have made and invented a certain new and useful Pen or Pencil Holder; and I do hereby declare that the following is a full, clear, and exact description of the same, reference being had to the accompanying drawings.

10 My invention relates to an improvement in that class or construction of holder which consists of a thimble or socket to be worn over the end of the forefinger; and my improvement therein consists in making the holder of two tubular parts or sections to slide upon each other, the outer tube forming a case for the inner one, and constituting a socket to cover and reach up over the first joint of the finger, and the inner tube holding the pen or pencil and capable of movement into and out from the outer tube. This construction, as hereinafter more fully described, produces a simple and serviceable holder of the kind which is capable of being closed up to protect 15 the point of the pen or pencil. When extended it affords a novel and effective means of holding the marking-point securely, while leaving the hand free.

20 The following description fully explains the nature of my said improvement and the manner in which I proceed to construct and apply the same, reference being had to the accompanying drawings by figures and letters—that is to say:

25 Figure 1 is a longitudinal section through a holder of my improved construction, with the inner tube extended ready for use. Fig. 2 is a top view of the holder when closed. Fig. 3 is a transverse section through the view Fig. 1. Fig. 4 is a similar cross-section, showing the construction adapted to receive a pencil. Fig. 5 is a view of the inner tube removed from the holder.

30 A represents a tube of suitable size to receive the end of the finger and fit snugly thereon. B is an inner shorter section adapted to

slide within the section A. The two are attached together by the screw c, which takes into the inner slide through a slot, d, in the outer tube, and is adapted to slide back and forth when pushed to one end or the other of the slot.

35 E is a raised or struck-up portion of the outer tube, in which the clamping part f of the inner section is received. This clamp is constructed to receive and hold either a pen or a pencil. The one construction (shown in Fig. 3) is employed when the holder is to receive a pen, and the other (represented in Fig. 4) is designed to hold a pencil-point. Such an instrument can be readily carried on the finger by a workman or salesman without interfering with the free use of the hand. It is also capable of being closed into small compass to protect the point or be carried in the pocket. 40 The length of the socket affords sufficient hold to the finger, and by extending up over the first joint maintains the required rigidness of the finger end to properly control and manipulate the marking-point.

45 In the use of ink the finger is covered and protected from soiling. The hand of the writer is also relieved of the cramped condition of the fingers and the work is rendered less tiresome.

50 As heretofore in use, finger-holders have been constructed with a single sheath. Pencil-points made movable and set by means of a slit and screw have been known.

55 Having thus fully described my invention, what I claim, and desire to secure by Letters Patent, is—

60 The combination of the finger-socket A with the inner sliding section, B, having the pen or pencil holder b, and the screw c, connecting the two parts and working through the slit d in the socket, substantially as described.

WM. LANE. [L. S.]
